ISABEL M. LEWIS, OF WASHINGTON, DISTRICT OF COLUMBIA.

MEDICINE-ADMINISTERING DEVICE.

1,215,823.

Specification of Letters Patent. Patented Feb. 13, 1917.

Application filed May 9, 1916. Serial No. 96,406.

To all whom it may concern:

Be it known that I, ISABEL M. LEWIS, a citizen of the United States, residing at Washington, District of Columbia, have invented certain new and useful Improvements in Medicine-Administering Devices, of which the following is a specification.

This invention relates to an improved device for use in administering medicine and the principal object of the invention is to provide the improved medicine administering device with improved means for controlling the passage of fluid or other material out of the outlet spout and to further so construct the device that it may be easily taken apart and thoroughly cleaned.

Another object of the invention is to provide a medicine administering device so constructed that medicine can be readily given to young children and persons unable to sit upright without danger of spilling the medicine.

It often happens that young children and persons suffering from certain diseases will resist taking medicine and sometimes food and it is then very difficult to administer the medicine with a spoon as the child or sick person will struggle and thus cause the medicine to be partially or sometimes entirely spilled from the spoon before the spoon can be inserted into the mouth. With this device the medicine cannot be spilled as the outlet spout is first inserted into the mouth and the outlet opening then uncovered.

This invention is illustrated in the accompanying drawings, wherein:

Figure 1 is a view in side elevation of the improved medicine administering device.

Fig. 2 is a view showing the improved device principally in vertical section and partially in elevation.

Fig. 3 is a transverse sectional view through the outlet spout taken along the line 3—3 of Fig. 2.

The cup or body portion 10 of this device is provided with an outlet spout 11 which extends from the cup 10 and fits into the sleeve 12 which is slidably mounted upon the spout. A plug 13 is secured in the lower end of the sleeve 12 and has its inner end portion 14 reduced as clearly shown in Fig. 2 so that the spout 11 may fit between the inner end of the plug and the sleeve 12.

Outlet openings 15 are provided in the sleeve so that when the sleeve is lowered, fluid can pass out through the sleeve.

The cup or bowl 10 is provided with a cover 16 which is screwed upon the bowl 10 so that it may be removed when placing the liquid or powder in the bowl and is provided with an air outlet spout 17 having a removable cap 18 so that when emptying the bowl, the cap may be removed thus permitting air to enter the bowl. It will thus be seen that when in use, the liquid will be placed in the bowl or cup 10 and after the cap or cover 16 has been put in place and the spout placed in the patient's mouth, the bowl being held and the sleeve supported by the fingers engaging the flange or collar 19, the sleeve can be lowered to the dotted line position which will bring the line 20 to a position in which it may be seen above the flange. The outlet opening 15 will now be opened and the liquid can flow out through the bottom of the spout 11 and out through the outlet openings 15. After a sufficient quantity of the liquid has flowed out through the spout, the sleeve can be again raised to close the outlet opening and the cap 18 put in place. Of course, if desired a measured quantity can be placed in the bowl and the entire amount permitted to flow out the outlet opening. This bowl could also be provided with indicating markings as shown at 21 so that the amount placed in the bowl could be readily ascertained and also the amount permitted to pass out of the bowl determined.

I have therefore provided a very simple structure which is very effective in operation and which is so constructed that it may be entirely taken apart for easy cleaning and sterilizing with hot water.

What is claimed is:

1. A medicine administering device comprising a bowl, an outlet spout leading from said bowl, a sleeve fitting upon said outlet spout, a closure plug for the lower end of said sleeve provided with a reduced inner end portion for fitting into the lower end of said outlet spout, said sleeve being provided with side openings, constituting outlet openings, and a cover for said bowl.

2. A medicine administering device comprising a bowl, an outlet spout leading from said bowl, and a sleeve slidably mounted upon said outlet spout and closed at its

lower end and provided with a side opening constituting an outlet opening closed by said spout when the sleeve is in a raised position.

3. A medicine administering device comprising a bowl having an outlet spout, a sleeve slidably mounted upon said bowl and provided with an engaging flange at its upper end, said bowl being closed at its lower end and provided with outlet openings in the sides, and a closure for said bowl.

4. A medicine administering device comprising a bowl, an outlet spout extending beneath said bowl and open at its lower end, an open ended sleeve slidably mounted upon

said spout and provided with side openings 15 constituting outlets, a supporting flange extending from the upper portion of said sleeve, and a closure plug fitting within the lower end of said sleeve against the lower end of said spout and provided with a reduced inner end portion fitting into the spout.

In testimony whereof I affix my signature in presence of two witnesses.

ISABEL M. LEWIS.
